United States Patent Office

Des. 177,713
Patented May 22, 1956

177,713

DISPLAY STAND

Lester B. Bracken, St. Albans, Vt., assignor to Standard
Packaging Corporation, Chicago, Ill., a corporation of Virginia

Application December 1, 1954, Serial No. 33,354

Term of patent 14 years

(Cl. D80—9)

Fig. 1.

Fig. 2.

Fig. 3.

Fig. 4.

I claim:

The ornamental design for a display stand, substantially as shown.
